E. J. HAHN

TANK CLEANER

Filed May 5, 1925

UNITED STATES PATENT OFFICE.

EDWARD J. HAHN, OF GRIDLEY, KANSAS.

TANK CLEANER.

Application filed May 5, 1925. Serial No. 28,186.

This invention relates to a tank cleaner, and particularly to a construction by which the sediment or sludge which collects at the bottom of a tank may be agitated and moved 5 toward a chute or passage so that the tank may be thoroughly and conveniently cleaned before being refilled.

In the use of a storage tank for oil or other liquids the standing body deposits more or 10 less sediment adjacent the bottom of the tank and under some conditions a body of thicker liquid collects at that point which must be separately collected. The cleaning of such a tank manually involves delay, in 15 convenience and danger owing to the presence of collected gas therein, while previous constructions for mechanically effecting such cleaning have involved much manual labor and failed to secure effective results within 20 a minimum time and by a simple operation.

To obviate these objections I have provided a blade member disposed adjacent the bottom of the tank and rotated therein to loosen any collected sediment and carrying 25 with it any oil unfit for use to a discharge chute or passage leading from the base of the tank. Such heavier collected matter will not normally flow to a discharge opening and must be bodily scraped or moved 30 into the discharge chute from which it may be withdrawn or flushed out as found most convenient. It has also been found desirable to adjust the blade vertically relative to the bottom of the tank to properly act upon 35 the material at that point, and further to provide a tank structure especially adapted to support such a cleaning device at its center so that the sweep of the cleaning blade may effect a practically complete action over 40 the bottom of the tank.

The invention has for an object to provide a novel and improved construction comprising a rotatable shaft adapted to be supported within a tank and provided with a 45 laterally projected blade disposed adjacent the bottom of the tank.

A further object of the invention is to provide a structure of a tubular rotating shaft having an inner shaft carrying the 50 blade which is vertically adjustable upon the rotating shaft to vary the distance of said blade to the bottom of the tank.

Another object of the invention is to provide a special form of tank for supporting 55 such a cleaning device and involving a bear-

ing at the base of the tank and a cooperating bearing at the top thereof, together with bracing means extending from the sides of the tank to the upper bearing.

Other and further objects and advantages of the invention will be hereinafter set forth and the novel features thereof defined by the appended claims.

In the drawings:

Figure 1 is a vertical section through a 65 tank having the invention applied thereto;

Figure 2 is a detail perspective of the blade connection with its adjusting rod;

Figure 3 is a similar view of the lower 70 end of the rotating shaft;

Figure 4 is a detail section of the upper end of said shaft with the adjusting means for the rod; and

Figure 5 is a detail elevation of the pawl and ratchet driving mechanism for rotating 75 the shaft.

Like reference characters designate corresponding parts throughout the several views.

The invention is applicable to any type of 80 tank or container and is particularly designed for use in connection with an oil tank in which there is a collection from the standing oil of more or less sediment or heavy material adjacent the bottom thereof which 85 should be periodically removed to prevent its remixture with the contents of the upper portion of the tank through any agitation due to refilling the tank. This removal or cleaning may be effected when the tank is 90 empty or even if the tank be filled, as the superposed body of liquid would act under such conditions to force the collected sediment from the discharge chute.

In the application of the invention shown, 95 the tank 10 is of the usual construction having the base or bottom 11 and the top 12. This base is formed at any desired point with a downwardly inclined discharge chute or passage 13 which extends radially from 100 the center of the tank and is closed at its outer end by a removable head 14 where a suitable draw-off cock 15 may be provided. The base of the tank has at its center a bearing step 16 upon which the lower end of 105 the tubular driving shaft 17 is supported in any preferred manner, for instance by means of the conical bearing 18 threaded into the end of the shaft 17 as shown in Figure 3. The lower portion of this shaft is further 110

provided with an elongated slot 19 through which the stirring or moving blade 20 passes. This blade is rigidly connected to an adjusting rod 21 disposed within the 5 shaft 17 and the slot 19 provides for a vertical adjustment of the blade relative to the base of the tank. The free end of the blade may be supported by a brace 20^a extending to the rod 21.

10 This adjustment may be secured by any desired means, for instance that shown in Figure 4 where the shaft 17 is supported within a bearing 22 carried by the top 12 of the tank and also has keyed thereon a 15 bevel gear 23 for the purpose of rotating the shaft. The rod 21 is threaded at its upper end 24 and extends above this bearing so as to receive a threaded nut or collar member 25 bearing at its lower end upon 20 the gear and top of the shaft 17. This nut is provided with a hand hold 26 by which it may be rotated for the purpose of adjusting the blade, as will be obvious.

Numerous means may be provided for rotating the shaft 17 through the gear 23 and one form is herein shown where a bevel gear 27 meshes with the gear 23 and has its extended shaft 28 supported in a bearing standard 29. This shaft carries a ratchet 30 gear or wheel 30 secured thereto and adapted to be operated in opposite directions by means of a double pawl 31 carried by the lever 32 which is loosely mounted upon the shaft 28. As shown in Figure 5 this pawl 35 is pivoted at 33 and held in its opposite shifted positions by means of a tension spring 34. It will be seen that a reciprocatory motion of the lever transmits a rotary drive to the shaft and blade or paddle operated thereby.

In mounting the cleaning device in a tank it is desirable to provide bracing members for the upper or driven ends of the shaft at its connection with the tank top and for 45 that purpose a series of brace rods 35 may be secured to the side walls of the tank and are formed with diagonally disposed portions 36 extending to the axis of the tank where the bearing 22 for the shaft is secured. This bearing and the driving mechanism may be suitably enclosed by a casing 37 and the tank is formed with the usual 50 openings for access thereto and to permit the escape of collected gas. As shown in Figure 1 the tank is connected with other tanks of a series by pipes 38 at opposite sides thereof, while the usual pipe line connection 39 is provided at the lower portion of the tank and the ladder 40 extends downward 55 from the man hole 41.

The operation of the invention will be apparent from the foregoing description from which it will be seen that a rotary movement of the blade will force the heavy material or liquid adjacent the bottom of

the tank toward and into the discharge chute therefrom while the blade or paddle for this purpose may be adjusted so as to lie in proper relation to the bottom of the tank without contacting therewith which 70 would involve damage to the parts.

While the specific construction of the several parts has been shown and described, still the invention is not confined thereto as changes and alterations may be made without departing from the spirit thereof as defined by the appended claims.

Having thus described my invention, what I claim as new and desire to secure by Letters Patent is:

1. A cleaning device for tanks comprising a rotatable shaft adapted to be supported therein, a blade laterally projecting from the lower end of the shaft and disposed adjacent the bottom of the tank, and means disposed at the upper end of said shaft for adjusting the blade longitudinally thereof.

2. A cleaning device for tanks comprising a rotatable shaft adapted to be supported therein; a blade laterally projecting from the lower end of the shaft and disposed adjacent the bottom of the tank, and means accessible from outside of the tank for adjusting said blade relative to said bottom while in driving relation with said shaft.

3. A cleaning device for tanks comprising a tubular shaft, means for rotating said shaft, an adjusting rod therein, and a blade carried by said rod and extending through said shaft.

4. A cleaning device for tanks comprising a tubular shaft, means for rotating said shaft, an adjusting rod therein, a blade carried by said rod and extending through said shaft, and means at the upper end of said shaft for adjusting said rod and blade.

5. A cleaning device for tanks comprising a tubular shaft, means for rotating said shaft, an adjusting rod therein, a blade carried by said rod and extending through said shaft, and a nut member engaging the upper end of said shaft and threaded upon said rod to adjust the same vertically.

6. A cleaning device for tanks comprising a tubular shaft provided at its lower portion with an elongated slot a bearing carried by the lower end of said shaft, an adjusting rod within said shaft, and a blade extending through said slot and secured to said rod.

7. A cleaning device for tanks comprising a tubular shaft slotted at its lower end, an adjusting rod within said shaft, a blade extending through the slot of the shaft and secured to said rod, means at the upper end of the shaft for adjusting said rod, a gear secured to the upper portion of said shaft, a cooperating driving gear meshing with the shaft gear, a ratchet wheel secured to the shaft of the driving gear, and a lever

loosely mounted upon said shaft and provided with a pawl to engage said ratchet wheel.

8. A tank provided with a bearing at its base, a shaft mounted thereon and supported at its upper end by a bearing at the tank top, means for rotating said shaft disposed at the top bearing thereof, a rod disposed within said shaft and a blade carried by the lower end of said rod and extended laterally to travel over substantially the entire base area of the tank.

9. A tank provided with a bearing at its base, a shaft mounted thereon and supported at its upper end by a bearing at the tank top, ¹⁵ means for rotating said shaft disposed at the top bearing thereof, a blade extending from the lower end of said shaft to travel parallel to the tank bottom, and a radial discharge chamber beneath the bottom of said tank ²⁰ and open at its top to communicate therewith.

In testimony whereof I affix my signature.
EDWARD J. HAHN.
